UNITED STATES PATENT OFFICE

2,334,981

OPENER FOR SLIDING DOORS

Percy A. Ackley, Manhattan Beach, Calif.

Application May 5, 1941, Serial No. 391,875

5 Claims. (Cl. 268—53)

My invention relates to power driven means for opening sliding doors and relates in particular to a power driven device of simple and economical construction which may be mounted within a relatively thin hollow wall of the door opening in which a sliding or rolling door is operable.

My invention is especially suited for use in residences wherein it is now a long established practice to extensively employ swinging doors, hinged at one side so as to swing when opened, into space adjacent the door within a room or hallway. Such door arrangement requires provision of space, in the arrangement of furniture, etc., into which the door may be swung, when opened. Likewise, swinging doors involve a constant element of danger in that a person opening a door from one side may cause the door to strike a person standing on the other side of the door, this being expressly noticed in doors of the double swing type employed between a kitchen and an adjoining room. Architects, at the present time, are seriously considering the use of sliding doors in residence construction, in view of the satisfactory manner in which the use of sliding doors solves the problems or corrects the undesirable conditions referred to in the first part of this paragraph. It is an object of my present invention to provide means whereby a sliding door may be opened and closed with complete safety to the users. That is to say, in the use of my invention, the power means of the device is employed in such a manner that the force thereof can under no circumstances be applied to injure a person or a part of a person in the doorway during the closing movement of the door.

A further object of the invention is to provide a door operating device wherein a power drive movable member engages the door or a projecting part thereon, only during the action of opening the door, permitting, if desired, the use of other means to close or open the door.

An object of the invention is to provide a power driven door opening device which will make engagement with a part of the door for the purpose of moving the door into open position, and will be disengaged from the door so that the door may be then closed as desired by hand.

A further object of the invention is to provide a door opening device for exerting on or applying to the door, a door opening force, other means being provided to apply to the door a closing force which is of just sufficient magnitude to move the door from open to closed position.

A further object of the invention is to provide a control means for sliding doors having a power

driven part for opening the door and an arrangement whereby the closing movement of the door is controlled to a predetermined speed, without application of force to the door by the motor of the device during the closing movement of the door.

A further object of the invention is to provide a door operating device of simple form having a continuous belt, preferably of D form through which movement is transmitted to the door, thereby effecting substantially silent operation in the use of the device. Herein I employ the term "sliding door" to indicate those doors whether or not supported on rollers, which move bodily in a vertical plane from a position to close a door opening to a position at one side, in contradistinction to hinged doors.

Further objects and advantages of the invention will be brought out in the following part of the specification.

Referring to the drawings, which are for illustrative purposes only:

Fig. 1 is a plan view of a preferred embodiment of my invention.

Fig. 2 is an elevational view corresponding to Fig. 1 and showing the upper portion of a sliding door in cooperative relation to the device.

Fig. 3 is an enlarged fragmentary sectional view taken as indicated by the line 3—3 of Fig. 2.

Fig. 4 is an elevational view showing an alternative form of my invention in association with the upper part of a sliding door.

Fig. 5 is a plan view of the door operating mechanism shown in Fig. 4.

Fig. 6 is an enlarged cross section taken on a plane indicated by the line 6—6 of Fig. 4.

The sliding door operating device shown in Figs. 1 to 3 inclusive is essentially a self-contained unit which may be placed in a wall space above a sliding door. This unit includes an elongated frame 10 having a plate 12 which carries a motor 11, which motor is preferably of the type having an attached reduction gear unit 13 arranged to drive a pulley 14 which is connected through a belt 15 with a driven pulley 16 fixed on a shaft 17 which is carried at one end of the frame 10 and has thereon a pulley 18 disposed so as to rotate in a vertical plane and in alignment with a pulley 19, disposed at the opposite end of the device.

The pulley 19 is carried by an adjustable support 20 having a pair of longitudinal bars 21 which slide into openings 22 in a block 23 which forms the leftward end of the frame 10. Springs 24 are disposed around the bars 21, and operate to urge the supports 20 in leftward direction so that the

traveler 25, which is in the form of a continuous loop, will be maintained substantially taut at all times. The traveler 25 consists of what is now commonly known as a V-belt, molded as a continuous loop from rubber and fabric, or made up from a length of V-belt stock with the ends joined by the customary connector. The motor 11 is arranged to drive the pulley 18 in clockwise direction so that the lower run 26 of the belt 25 will travel leftward, or, in other words, in a direction to open a door 27 which is hung below the door operating device.

As shown in Fig. 3, the door 27 is hung from parallel tracks 28, which may be made of wood, by means of two suspension units 29, each of which may comprise a central suspension plate 30, having a detachable bracket 31 at its lower end to be connected by means of screws to the upper end of the door 27. The upper portion of the suspension plate carries a lateral bronze bushing 32 arranged for the support of a pair of rubber rollers 33 to roll on the portions of the track members 28 adjacent the suspension plate 30. The track members 28 have longitudinal guide shoulders 34 placed as shown, whereby the wheels or rollers 33 will be guided in such a manner that the suspension plate 30 will be maintained centralized relative to the space between the track members 28 and, therefore, the upper edge of the door 27 will be maintained centralized between the molding strips 35, which are employed to conceal the upper edge of the door 27.

The front suspension unit for the door 27, in this instance the rightward suspension unit 29, has an upwardly projecting engagement element or post 36 adapted, when the door 27 is in its closed position, as shown in Fig. 2, to lie in the path of movement of a lug 37 carried by the belt 25, when the motor 11 is operated to rotate the pulley 18 in clockwise direction so that the lug 37 will be caused to move downward and then leftward toward the position of the lug 38. It will be perceived accordingly that the lug 37 when it is so moved, will engage the post 36, and the movement of the lug 37, due to the travel of the belt 25 will be transmitted through the post 36 to the door 27 to move the same from the leftward position in which it is shown in Fig. 2. Therefore, the lug 37 will carry the post 36 leftward into the position thereof indicated by dotted lines 38', at which time the lug 37 will move upwardly around the pulley 19, and will be disengaged from the post 36, leaving the door 27 in open position, from which open position the door 27 may be closed by any other suitable means, as, for example, by hand. Separate means for the closing of a door will be described in detail with relation to Figs. 4 and 5.

The motor 11 is connectable with conductors 40, leading to a source of current, by the well known type of remotely controlled switch 41, having an electromagnetic hold-in which releases or opens the switch when the hold-in circuit is broken. A start circuit 42 is connected with a suitable start switch placed conveniently to the door opening. The hold-in circuit 44 is equipped with a manually operated push button switch 45, whereby the hold-in circuit may be opened, and with a switch 46 having a lever 47 which projects into the path of movement of the lug 37, as such lug 37 moves rightward and downwardly around the pulley 18 into the position in which it is shown in Fig. 2, whereby the lug 37 will displace the lever 47 in the manner shown in Fig. 2 so as to open the switch 46, which will result in automatically

opening the hold-in circuit and releasing the switch 41 so that the motor will be stopped with the lugs 37 and 38 in inactive position.

In the use of a belt 25, I achieve quietness of operation. A feature of the device, in addition to other features brought out herein, is the provision of a guide 48 for the lower run 26 to the belt 25. This guide comprises a downwardly faced channel having branches 49 to engage the side walls of the lower run of the belt, so that the lower run of the belt will not be deflected laterally or upwardly.

In Figs. 4 and 5 I show a form of my invention which is in general similar to the form shown in Figs. 1 and 2, but has pulleys or sheaves 50 and 51, corresponding to the end pulleys 18 and 19, but which are mounted so as to rotate on vertical axes so that a belt 52 carried thereover, will lie and move in a horizontal plane. This form of the device includes a frame 53 with channel belt guides 54 along both sides thereof. At one end of the frame 53 there is a bracket 55 supporting a shaft 56 which has a sheave 57 on its upper end, and has fixed to its lower end the pulley 50. On the opposite end of the frame 53 there is a block 58 having openings 59 which receive the parallel guide bars 60 of a pulley support 61 which is constantly urged outward so as to maintain the belt taut by springs 62.

A motor drive unit 63 has a pulley 64 connected to the sheave 57 by a belt 65. It will be understood that any type of suitable switch control may be employed with the motor 63. In Fig. 5 I have shown a stop switch 66 having a contact member 67 arranged to be engaged by a lug 68 mounted on the belt 52.

A door 69 is shown in Fig. 4 in operative position beneath the device. The door 69 has an engageable part comprising an upwardly projecting post 70 positioned so as to be engaged by an engager 71 supported by an arm 72 which projects inward from the lug 68 through a distance substantially equal to the distance of the lug from the center of the pulley 50 so that the engager 71 will be positioned on the axis of the pulley 50 when the lug 68 is contiguous to the pulley, and will at all times lie in a vertical plane defined by the axes of the pulleys 50 and 51. Accordingly, when the motor 63 drives the belt 52, the engager 71 will move along a horizontal path above the upper edge of the door 69, and when travel of the belt 62 moves the engager 71 leftward from the position in which it is shown in full lines in Fig. 4, the engager 71 will come into engagement with the post 70 and will then move the post 70 and the door 69 leftward, and when the lug 68 engages the lever 67' of the stop switch 66, the motor 63 will be stopped with the engager 71 in a position on the axis of the pulley 51, to hold the door 69 in open position.

In Fig. 4 I have shown a door closing means arranged to yieldably exert a door closing force, such means comprising a weight 75 connected to the door 69 by a cable 76 which runs over a sheave 77. After the door 69 has been opened by the device in the manner above described, the motor 63 may be again actuated so as to cause the engager or pusher 71 to move from its position under the sheave 51 to its initial position shown in full lines in Fig. 4, below the sheave 50. As the engager 71 moves rightward at constant speed, under control of the motor, the force exerted by the weight 75 through the cable 76 will tend to move the door 69 rightward and will hold the post 70 in engagement with the engager 71,

with the result that the door 69 will pass through a closing movement, but the rate of the movement of the door will be controlled by the movement of the engager 71. Should there be an object, such as a bodily part, in the path of movement of the door 69, as the movement of the engager 71 permits a closing movement of the door by the weight 75, the door 69 will be brought to rest and no pressure will be brought against the bodily part to injure the same, other than the small pressure resulting from the weight 75, there being no connection between the engager 71 and the post 70 whereby force from the motor 63 may be transmitted to the door during its closing movement.

I claim as my invention:

1. In a sliding door operating device adapted to be mounted adjacent a horizontal edge of said door, the combination of: a support carrying spaced pulley means; a loop-shaped traveler carried by said pulley means; power means to selectively move said traveler through a cycle of operation; and an engager on said traveler for engagement with a part on said door whereby said door will be moved in a selected direction by movement of said traveler, said engager comprising an arm having one end thereof rigidly connected to said traveler and extending toward the plane defined by the axes of said pulley means, the other end of said arm being prepared for engagement with said part on said door.

2. In a sliding door operating device adapted to be mounted adjacent a horizontal edge of said door, the combination of: a support carrying spaced pulley means so that they will rotate on substantially vertical axis; a loop-shaped traveler carried by said pulley means; power means to selectively move said traveler through a cycle of operation; and an engager on said traveler for engagement with a part on said door whereby said door will be moved in a selected direction by movement of said traveler, said engager comprising an arm having one end thereof rigidly connected to said traveler and extending toward the plane defined by the axes of said pulley means, the other end of said arm being prepared for engagement with said part on said door.

3. In a sliding door operating device adapted to be mounted adjacent a horizontal edge of said door, the combination of: a support carrying spaced pulley means so that they will rotate on substantially vertical axis; a loop-shaped traveler carried by said pulley means; power means to selectively move said traveler through a loop-shaped cycle of operation; an engager on said traveler for engagement with a part on said door

whereby said door will be moved in a selected direction by movement of said traveler, said engager comprising an arm having one end thereof rigidly connected to said traveler and extending toward the plane defined by the axes of said pulley means, the other end of said arm being prepared for engagement with said part on said door; control means operative to start the operation of said power means; and stop means engageable by a part of said traveler to stop said power means when said traveler reaches the end of its cycle of movement.

4. In a sliding door operating device adapted to be mounted adjacent a horizontal edge of said door, the combination of: a support carrying spaced pulley means so that they will rotate on substantially vertical axis; a loop-shaped traveler carried by said pulley means; power means to selectively move said traveler through a loop-shaped cycle of operation; an engager on said traveler for engagement with a part on said door whereby said door will be moved in a selected direction by movement of said traveler, said engager comprising an arm having one end thereof rigidly connected to said traveler and extending toward the plane defined by the axes of said pulley means, the other end of said arm being prepared for engagement with said part on said door; control means operative to start the operation of said power means; and stop means engageable by a part of said traveler to stop said power means when said traveler reaches the end of its cycle of movement, said stop means comprising a stop switch placed adjacent the path of movement of said traveler around one of said pulley means and so as to be engaged by said engager as it travels around said pulley means.

5. In a sliding door operating device adapted to be mounted adjacent a horizontal edge of said door, the combination of: a support carrying spaced pulley means; a loop-shaped traveler carried by said pulley means; power means to selectively move said traveler through a cycle of operation; and an engager on said traveler for engagement with a part on said door whereby said door will be moved in a selected direction by movement of said traveler, said engager comprising an arm having one end thereof rigidly connected to said traveler and extending toward the plane defined by the axes of said pulley means, the other end of said arm being positioned so that it will lie continuously in said plane throughout movement of said engager by said traveler and being prepared for engagement with said part on said door.

PERCY A. ACKLEY.
